Application August 9, 1954, Serial No. 31,784

Term of patent 14 years

(Cl. D54—13)

Fig. 1

The characteristic features of the pair of pliers disclosed reside in the raised ornamentation on the handles having the configuration or pattern shown.

I claim:

The ornamental design for a pair of pliers, as shown and described.
